UNITED STATES PATENT OFFICE.

SEYMOUR W. BONSALE, OF NEW YORK, N. Y., ASSIGNOR TO INNOVATION TRUNK COMPANY, A CORPORATION OF NEW YORK.

DRIER.

1,115,051.

Specification of Letters Patent.

Patented Oct. 27, 1914.

Application filed November 17, 1911. Serial No. 660,819.

To all whom it may concern:

Be it known that I, SEYMOUR W. BONSALE, a citizen of the United States, residing in the borough of Manhattan, city, county, and State of New York, have invented certain new and useful Improvements in Driers; and I do hereby declare the following to be a full, clear, and exact description of the invention, such as will enable others skilled in the art to which it appertains to make and use the same.

My invention has relation to means whereby lumber may be quickly and conveniently dried, and the principal object of the invention is the provision of means whereby a powerful draft of heated air may be produced in a suitably disposed group of boards, planks, veneer or other sawed lumber, whereby the moisture held within the fibers thereof may be quickly and uniformly carried off.

My improved apparatus comprises broadly a revolving container provided with suitable supports for the wood to be treated and with means whereby air entering near the center of the container is preheated and driven outward around and past the properly disposed boards or planks.

My invention is shown in certain preferred embodiments in the accompanying drawings, wherein—

Figure 1 is an external side elevation of one form of the apparatus, Fig. 2 is a median vertical section of the same, and Fig. 3 is a plan view of the same with a portion of the top removed.

The main container is composed of an outer cylindrical casing 10 made of perforated construction in any desired manner, and preferably of wire mesh, as shown; the same being reinforced by external hoops or bands 11. The casing 10 is carried by a floor 12 having a central aperture 13, and mounted upon roller bearings 14 or the like, carried by any suitable base 15. The circular top frame 16 has spider arms 17 uniting in a hub 18, whereby the entire device may be revolved at a suitable speed by any appropriate means. While I do not limit myself to any particular means for revolving the casing, I have shown in Fig. 1, an electric motor 19 whose armature is connected to a shaft 20, which is fastened to the hub 18.

One or more sections of the casing 10 is

made removable, and may be secured in place by any suitable fastenings 21, 22. This permits ready access to the interior of the casing, whereby the boards 23 may be erected in place, for instance, in suitable sockets, racks or grooves 24, at top and bottom of the container. The top of the container is provided with a deflector 25, whereby the air which tends to enter at the top is directed toward the center.

A two part steam pipe 26 is carried in an axial position by the container, and a double drum 27 at the bottom, which is stationary, serves to feed steam to said pipe from the pipe 28 and to carry off steam therefrom by the exit pipe 29. The steam passes upward through one half of the pipe 26, outward through the spiral top coil 30, and back into the second half of the axial pipe, whence it is discharged at 29.

When the container is made to revolve, the centrifugal action will draw air inward at top and bottom at the center, where it is heated by the steam pipes, and will drive it outward past the standing boards 23, to leave through the open work casing 10, all as indicated by the arrows in Fig. 2.

In order to insure a more uniform distribution of the air currents, I prefer to employ graduated distributors in the path of the same. In the specific form shown these take the form of concentric cylinders of wire mesh 31, surrounding the pipe 26 near the central air entrances and made successively longer; so that, as the air approaches the middle of the container, less and less resistance to flow is opposed by the meshes. The proportional distance apart of the cylinders 31 is exaggerated in the drawings, and it is also to be understood that the arrangement, number and size of these elements are not essential to my invention. Indeed, so far as this feature of my preferred invention is concerned it is broad enough to cover the use of any devices for distributing the air currents so as to secure substantial uniformity.

A variety of changes may be introduced in this device without departing from my invention, and I do not limit myself to the details herein shown and described.

What I claim is—

1. A wood drier comprising a revoluble container for timber having a substantially axial admission opening for air, and a suit-

- able exit opening therefor, and heating means located near the axis of the container in the path of the entering air, substantially as described.
5. 2. A wood drier comprising a revoluble container for timber having a substantially axial admission opening, and a suitable exit opening therefor, and an axial steam pipe in said container in the path of the entering air, substantially as described.
10. 3. A wood drier comprising a revoluble container for timber having a substantially axial admission opening for air, and a suitable exit opening therefor, an axial two-part steam pipe in said container, and means for conducting steam into one part of said pipe and out of the other part, substantially as described.
15. 4. A wood drier comprising a revoluble container for timber having substantially axial admission opening for air, and a suitable exit opening therefor, an axial two-part steam pipe in said container having an extension leading from one part of said pipe to the other, and means for conducting steam into one part of said pipe and out of the other part, substantially as described.
20. 5. A wood drier comprising a revoluble container for timber having substantially axial admission opening for air, and a suitable exit opening therefor, an axial two-part steam pipe in said container having a spirally disposed extension leading from one part of said pipe to the other, and means for conducting steam into one part of said pipe and out of the other part, substantially as described.
25. 6. A wood drier comprising a revoluble container for timber having substantially axial admission opening for air, and a suitable exit opening therefor, in combination with heating means located near the axis of the container in the path of the entering air and a distributer for securing substantially uniform air currents, substantially as described.
30. 7. A wood drier comprising a revoluble container for timber having substantially axial admission opening for air, and a suitable exit opening therefor, in combination with a distributer for securing substantially uniform air currents, substantially as described.
35. 8. A wood drier comprising a revoluble container for timber having substantially axial admission opening for air, and a suitable exit opening therefor, in combination with an axially disposed heating means and a distributer embracing said means for securing substantially uniform air currents, substantially as described.
40. 9. A wood drier comprising a revoluble container for timber having substantially axial admission opening for air, and a suitable exit opening therefor, in combination with an axially disposed heating means and perforated cylinders surrounding said heating means and adapted to oppose a gradually lessening resistance to the passage of air from the end of the container inward, substantially as described.
45. 10. A wood drier comprising a revoluble container for lumber having a deflector at one end leading to a substantially axial opening, in combination with a steam radiator carried by said container above said deflector, substantially as described.
50. 11. A wood drier comprising a revoluble casing of wire mesh, means for admitting air near the axis of the casing, and means for supporting the wood to be dried within said casing, substantially as described.
55. 12. A wood drier comprising a revoluble casing of wire mesh, means for admitting air near the axis of the casing, a cylindrical graduated wire mesh distributer surrounding the admission opening, and means for supporting the wood to be dried within said casing, substantially as described.
60. 13. A wood drier comprising a revoluble casing of wire mesh, means for admitting air near the axis of the casing, spider arms at the top of the casing uniting in a hub, driving means connected with said hub, and means within the casing for supporting the wood to be dried, substantially as described.
65. In testimony whereof, I affix my signature, in presence of two witnesses.
70. SEYMOUR W. BONSALL.
